CLAIM

The ornamental design for a manicure arm rest assembly, as shown and described.

DESCRIPTION

FIG. 1 is a front perspective view of a manicure arm rest assembly, showing both legs in an extended position in my new design.

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded bottom perspective view of the manicure arm rest assembly of my new design.

FIG. 9 is a front perspective view of the manicure arm rest assembly, showing both legs in a retracted position in my new design.

FIG. 10 is a front view thereof;

FIG. 11 is a back view thereof;

FIG. 12 is a left side view thereof;

FIG. 13 is a right side view thereof;

FIG. 14 is a top view thereof;

FIG. 15 is a bottom view thereof; and,

FIG. 16 is a bottom perspective view thereof, showing one leg in an extended position and another leg in a retracted position in my new design.
